(57) **CLAIM**

The ornamental design for a transformable toy, as shown and described.

DESCRIPTION

FIG. 1 is a front view of the transformable toy, shown in the form of a camera;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is another perspective view thereof;

FIG. 9 is a perspective view thereof, shown with the front part in an open position;

FIG. 10 is a front view of the transformable toy, shown in the form of a gun;

FIG. 11 is a rear view thereof;

FIG. 12 is a right side view thereof;

FIG. 13 is a left side view thereof;

FIG. 14 is a top view thereof;

FIG. 15 is a bottom view thereof;

FIG. 16 is a perspective view thereof;

FIG. 17 is another perspective view thereof; and,

FIG. 18 is another perspective view thereof; shown with the front part in an open position.

The broken lines shown represent portions of the transformable toy that form no part of the claimed design.

This product can reversibly change into a camera and gun form.

1 Claim, 16 Drawing Sheets
